UNITED STATES PATENT OFFICE.

GEORGE M. LITTLE, OF PITTSBURGH, PENNSYLVANIA, ASSIGNOR TO WESTINGHOUSE ELECTRIC & MANUFACTURING COMPANY, A CORPORATION OF PENNSYLVANIA.

TELESCOPING ELECTRODE PROTECTOR.

Application filed May 24, 1921. Serial No. 472,096.

To all whom it may concern:

Be it known that I, GEORGE M. LITTLE, a citizen of the United States, and a resident of Pittsburgh, in the county of Allegheny and State of Pennsylvania, have invented a new and useful Improvement in Telescoping Electrode Protectors, of which the following is a specification.

My invention relates to electric furnaces and particularly to electric-resistance furnaces and it has for its object to provide means for protecting the exposed portion of the carbonaceous electrode against the oxidizing effect of the surrounding air.

15 In my copending application, Serial No. 454,776 filed March 23, 1921, is disclosed an electric-resistance furnace in which the heating element comprises a plurality of carbonaceous plates which are maintained in 20 their proper operative positions, relatively to each other and in the furnace chamber, by means of a resilient compression means and a carbonaceous electrode which extends through one of the walls of the furnace.

25 I have found that the portion of the electrode just outside of the furnace wall operates at a temperature sufficiently high to permit of an oxidizing effect of the air upon the electrode.

30 In practicing my invention, I provide a mass of granular carbonaceous material surrounding that portion of the electrode extending between a water-cooled contact terminal located at the outer end thereof and 35 the outer face of the furnace and maintain the said mass in its proper operative position by means of a two-part telescoping container. One part of this container is secured to the outer surface of the furnace wall and

40 the other part is secured to the metallic contact terminal. As the electrode has limited longitudinal movement relatively to the furnace wall through which it passes, the two parts of the container are permitted to move 45 relatively to each other while maintaining the granular mass in its proper operative position.

In the single sheet of drawings:

Figure 1 is a view, in vertical cross-section, 50 of an electric-resistance furnace comprising the device embodying my invention, and

Fig. 2 is a view, in lateral cross-section, on the line II—II of Fig. 1.

An electric furnace 1 comprises a metallic 55 framework or casing 2 and suitable support-

ing members 3. Outer walls 4 comprise a plurality of bricks or blocks of a suitable heat-insulating material. Inner walls 5 comprise a plurality of bricks or blocks of a suitable high-temperature-resisting material. The walls 5 are suitably spaced apart to form a furnace chamber 6 of any suitable or desired contour and dimensions.

As a furnace of the above indicated character is intended to be employed to heat metallic articles, an opening 7 is provided in one of the walls of the furnace near the bottom of the chamber to permit of introducing and removing such articles.

A heating element 8 for the furnace comprises a plurality of flat carbonaceous members substantially of the character described in the hereinbefore mentioned application. The heating element or resistor 8 is compressed by means of an elongated carbonaceous electrode 9 extending through a suitable opening in one of the furnace walls and engaging, at its inner end, a graphite end plate 10.

A resilient compression means comprises 80 an adjustable screw 11 and a helical spring 12, the inner end of which operatively engages the outer end of the electrode 9, an insulating member 13 being interposed between the outer end of the electrode and the 85 helical spring to suitably insulate these members from each other. While I have illustrated a specific embodiment of the resilient compression means, I do not desire to be limited to this device as this is illustrated 90 schematically only and any suitable or desired resilient compression means may be employed.

A water-cooled metallic contact terminal 14 is suitably secured to the electrode 9 near 95 the outer end thereof and is provided with suitable connecting lugs 15 to which the ends of the supply-circuit conductors (not shown) may be connected. As the electrode 9 has limited longitudinal movement relatively to the wall of the furnace through which it passes, by reason of the expansion and contraction of the various portions of the electric furnace, when in operation, the contact terminal 14 must necessarily be located some 100 distance away from the furnace wall. This, of course, exposes a portion of the length of the electrode 9 and, as the temperature of this exposed portion of the electrode may become so high as to permit the same to be 110

oxidized by the air surrounding it, protecting means are provided. These means comprise a thin metal plate 16 of substantially **U**-shape secured against an insulating member 17 mounted on the out-side of the furnace casing 2 and a second plate 18 also of substantially **U**-shape, secured to an insulating member 19 which is bolted against the inner surface of the contact terminal 14. The member 18 secured to the contact terminal 14 is placed inside of, and engaging, the plate 16 over a portion of its length, the members 17, 16, 18 and 19 forming a container for a mass 20 of granular carbonaceous material placed therein to surround the electrode 9 over a portion of its length.

As the temperature of the electrode 9 at that portion of its length located inside walls 4 and 5 is relatively high, I provide means comprising a well or hopper 21 and a mass 22 of granular carbonaceous material surrounding that part of the electrode lying in the walls 4 and 5, to prevent the oxidizing effect of any air tending to flow along the electrode through the furnace chamber or of any air in which may leak in through the walls 4 and 5 between the individual bricks or blocks. This device is more fully described and claimed in my copending application, Serial No. 472,093, filed May 24, 1921.

It may be noted that the telescoping container comprising the metallic members 16 and 18 forms a relatively simple means for maintaining the mass 20 of granular carbonaceous material in its proper operative position around the electrode while permitting movement of one member relatively to the other member or part, as may be required by the movement of the electrode relatively to the furnace wall through which it passes.

Various modifications may be made in the device embodying my invention without departing from the spirit and scope thereof

and I desire that only such limitations shall be placed thereon as are imposed by the prior art or are specifically set forth in the appended claims.

I claim as my invention:

1. An electric furnace comprising a plurality of furnace walls enclosing a furnace chamber, a resistor in said chamber, a carbonaceous electrode extending through one of said walls for conducting current to and from said resistor and having limited longitudinal movement relatively to said wall, a water-cooled terminal mounted on said electrode at its outer end, granular oxidizable material surrounding said electrode between said wall and said terminal and a two part telescoping container for said granular material, one part being secured to said wall and the other part being located against said terminal.

2. An electric furnace comprising a plurality of furnace walls enclosing a furnace chamber, a resistor in said chamber, a carbonaceous electrode extending through one of said walls for conducting current to and from said resistor and having limited longitudinal movement relatively to said wall, a water-cooled terminal mounted on said electrode at its outer end, granular oxidizable material surrounding said electrode between said wall and said terminal and means for retaining said granular material in its operative position around said electrode irrespective of the movements of said electrode and said contact terminal relatively to said wall and a two-part telescoping container for said granular material, one part being secured to said wall and the other part being located against said terminal.

In testimony whereof, I have hereunto subscribed my name this 18th day of May, 1921.

GEORGE M. LITTLE.
